METHOD OF MAKING INNERSOLES

Frederick W. Eager, Arlington, Mass., assignor
to Beckwith Manufacturing Company, Boston,
Mass., a corporation of Massachusetts

Application April 8, 1930. Serial No. 442,522

1 Claim. (Cl. 12—146)

This invention relates to innersoles for those types of shoes wherein the upper materials are lasted over flat against the outer face of the innersole, such as McKay, Littleway, and cement process shoes. When such an innersole is a flat piece of substantially uniform thickness throughout, as heretofore constructed and the edges of the upper are lasted thereover, these edge portions form a marginal rib about the edge of the innersole which requires a filler to be applied to the central portion of the innersole in order that a substantially flat surface laterally of the shoe may be presented to receive the outersole. Commonly the upper margins are not lasted in about the heel seat of the innersoles so that a flat piece of suitable material covering the heel seat of the innersole and commonly called a "heel seat brace" must be applied to bring it into line with the lasted upper margins and the filler applied to the innersole therebetween.

According to the present invention the innersole is made with a marginal depression to receive the edges of the upper material, but to facilitate making such a construction and to permit the use of relatively thin cheap innersole stock, I preferably apply to the usual flat innersole face a composition layer which may form a combined filler and heel seat brace and then remove sufficient of the marginal portion of this layer material to form a pocket or depression to receive the edges of the upper. Thus a relatively thin innersole stock may be employed and yet provide the necessary filler thickness.

For a more complete understanding of this invention, reference may be had to the accompanying drawing in which

Figure 1 is a perspective of an innersole blank as heretofore made.

Figure 2 is a fragmentary diagrammatic section showing the method of applying the filler material to the innersole stock either before or after it is cut into innersole blanks.

Figure 3 shows in perspective a coated innersole blank, a part of the margin of the filler layer being cut away.

Figures 4 and 5 are cross sections through the forepart portions of fully prepared innersoles showing different methods of forming to receive the lasted edges of the upper.

Figure 6 is a cross section through the forepart of the lasted shoe, a portion of the upper material having been trimmed.

Figure 7 is a fragmentary perspective of the heel portion of a prepared innersole illustrating a modification.

Figure 8 is a fragmentary transverse section through the heel portion of a shoe showing the innersole of Figure 7 and provided with a wood heel.

Referring to the drawing, a suitable sheet 60 material of relatively thin stock, such as has heretofore been employed for the manufacture of innersoles for the flat innersole type shoes, such as McKay, Littleway process and cement process shoes are provided with a coating layer 3 of material suitable for use as a innersole filler. This material may well be formed from initially plastic material such as the mass shown at 4, which may be rolled onto one face of the sheet 1 to form a self-bonding layer of the desired thickness. Material suitable for this purpose should be capable of being rendered initially plastic and should adhere to the innersole and flex therewith during use without cracking, and without flowing too readily after having been once applied and hardened.

While many compositions might be used, one composition which is suitable for the purpose may be made up as follows: 2½ pounds of rubber in the form of smoked sheet; 1 pound of asbestos fiber; 1½ pounds of rosin; ¼ pound of ground cork; 1 ounce zinc oxide and 1 ounce of sulphur may be compounded in a mixer or mill. When the mass is reduced to the desired consistency it may be supplied to the nip between a pair of 85 rolls 10 and 11 as shown in Figure 2, these rolls being spaced so as to leave the desired uniform thickness of material on one face of the foundation layer of sheet material. This coating material should be applied while warm and then be 90 permitted to harden, and may be applied either before or after the sheet material is cut into the shape of innersole blanks, as shown in Figure 1, but preferably is applied before the blanks are cut, since it is then easier to insure a uniform 95 coating of the material.

After the material has solidified a portion about the margin of the innersole is cut to form a seat to receive the margin of the upper materials during the lasting operation. As shown 100 in Figures 3 and 4 this seat may be formed by removing the entire marginal portion of the coating layer as by channeling or by any other suitable method, the seat being shown at 15. In place of removing the whole thickness of the 105 coating layer it may be skived as shown at 16 in Figure 5. As shown in Figure 3, the seat is not formed to extend about the heel end portion of the innersole, the coating at this portion of the innersole being left its full thickness and form-

ing a heel seat brace as at 17 integrally connected with the filler portion 18 between the margins cut to receive the marginal edges of the upper.

As shown in Figure 6 these upper materials 5 as 20, including the outer upper materials 21 and the lining 22, may be lasted over the margin of the innersole and secured thereto by any suitable means, this means depending on the type 10 of shoe which is to be made. The margins of the upper materials which initially may extend inwardly of the seats 15 are then trimmed off, as shown at the left hand portion of Figure 6, so that the lower face of the upper materials at 15 their margins is substantially in lateral alignment with the lower face of the filler 18.

Instead of terminating the marginal seat of the innersole forwardly of the heel seat, it may be extended entirely around the edge including the heel end of the innersole, as shown at 20 25 in Figure 7, this seat being occupied not only by the upper materials, but by the attaching flange 26 of the counter stiffener 27, as shown in Figure 8. The central portion of uniform

thickness forms a heel seat brace as in the form previously described. Where a wood heel is used, as shown at 28 in this figure, the margin of the 80 outersole 29 is cut away in the usual manner so that the margin 30 of the wood heel may closely engage the upper.

From the foregoing description of certain embodiments of this invention, it should be evident to those skilled in the art that various changes and modifications might be made without departing from the spirit or scope of this invention as defined by the appended claim.

I claim:

The method which comprises applying a plastic composition to one face of innersole stock to 90 form a layer of a thickness suitable to form an innersole filler, permitting the layer to harden, and then removing sufficient of said layer about the margin of an innersole blank cut from such stock to form a seat to receive the lasted margin 95 of a shoe upper.
